Primary Examiner — T. Chase Nelson*Assistant Examiner* — Ania Aman(74) *Attorney, Agent, or Firm* — Banner & Witcoff, Ltd.(57) **CLAIM**

The ornamental design for an armored vehicle, as shown and described.

DESCRIPTION

FIG. 1 is a perspective view showing an armored vehicle showing our new design.

FIG. 2 is a top plan view.

FIG. 3 is a first side elevation view.

FIG. 4 is a second side elevation view.

FIG. 5 is a front side elevation view; and,

FIG. 6 is a rear elevation view.

The broken line showing of various features is for illustrative purposes only and forms no part of the claimed design.

1 Claim, 5 Drawing Sheets(56)
